(Cl. D91—3)

To all whom it may concern:

Be it known that I, Richard W. English, a citizen of the United States, residing at Jersey City, county of Hudson, State of New Jersey, have invented a new, original, and ornamental Design for a Pipe Coupling, of which the following is a specification, reference being had to the accompanying drawing, forming a part hereof.

Figure 1 is a top plan view of a pipe coupling, showing my new design.

Figure 2 is a front elevation thereof; and

Figure 3 is a perspective view thereof.

When viewed from the bottom, the coupling appears the same as it does in the top view of Figure 1, except that the heads of the clamping bolts would appear in place of the nuts received on the bolt shank.

I claim:

The ornamental design for a pipe coupling, as shown and described.

RICHARD W. ENGLISH.
